FOLLOWER MECHANISM FOR FILING-CABINETS.

1,280,328.

Specification of Letters Patent.

Patented Oct. 1, 1918.

Application filed May 29, 1913. Serial No. 770,613.

To all whom it may concern:

Be it known that I, EVERETT STUCK, of Syracuse, in the county of Onondaga and State of New York, have invented a certain 5 new and useful Follower Mechanism for Filing-Cabinets, of which the following is a specification.

This invention has for its object the production of a follower mechanism for filing 10 cabinets and the like, which is particularly simple in construction, easily operated without binding and highly efficient and durable in use; and the invention consists in the novel features of construction hereinafter 15 set forth and claimed.

In describing this invention reference is had to the accompanying drawing in which like characters designate corresponding parts in all the views.

20 Figure 1 is a cross-sectional view of a filing cabinet draw or the like illustrating in rear elevation the follower mechanism.

Fig. 2 is a central longitudinal sectional view of parts seen in Fig. 1.

25 Fig. 3 is a detail view of the slide of the follower mechanism.

Fig. 4 is a detail view of the follower.

1 1 is a draw or the like; 2 the follower; 3 the guide for the follower. 4 and 5 are re- 20 spectively the fixed and movable clamping members which coact with the guide 3 to hold the follower in any adjusted position along the guide 3.

The guide 3, as here shown, is in the form 35 of a channel having its side margins 6 over-hanging the bottom of the channel. The guide 3 is usually bent up of sheet metal and formed with slots 7 in its intermediate portion, which receive lugs 8 projecting from 40 the bottom 9 of the draw, the lugs being bent over onto the bottom of the channel to hold the guide in position.

The slide 4 moves in the channel of the 45 guide 3 and has its side margins engaging the under faces of the overhanging margins 6 and its intermediate portion connected to the follower 2. The slide is usually elongated and extends on opposite sides of the follower projecting farther in front of the 50 same than in the rear thereof; and the clamping member 5 coacts with the slide 4 at the rear end of the slide so that any rearward pressure applied to the follower, without operating the movable clamping mem-

ber 5, tends to tilt the slide about an axis 55 located at its rear end and hence the front end, which extends a considerable distance in front of the follower, binds and prevents unintentional movement rearwardly of the follower. The articles in the filing cabinet 60 press rearwardly on the follower and tend to tilt the follower and the slide when the follower is in snug engagement with the articles in the filing cabinet. Forward pressure on the follower is not resisted by the 65 forwardly extending portion of the slide.

The slide 4 is formed up out of sheet metal and the intermediate portion 10 is raised upwardly between opposing edges of said overhanging margins 6 so that the slide will 70 clear the lugs 8.

As here shown, the follower is formed with means as lugs 2^a projecting from the lower edge thereof and embracing the intermediate portion 10 of the slide 4, and 75 arms 11 rise from said intermediate portion 10 and pass close to ears 12 projecting rearwardly from the follower. The arms 11 are preferably formed integral with the slide, the slide with the arms being struck 80 from a sheet metal blank and the portion of the blanks from which the arms project, is unprovided with margins for running under the side margins of the guide.

The movable clamping member 5 is piv- 85 oted to the arms 11 and the ears 12 and co- 90 acts with the upper faces of the overhang- 95 ing margins 6 of the guide 3, near the rear end of the slide 4. This member 5 is usu- 95 ally formed with forwardly extending side flanges 14 which overlap and inclose the arms 11 and ears 12 and the pivot 16 of the member 5 extends through the flanges 14, ears 12 and arms 11 and holds the parts in their assembled position.

The clamping member 5 is spring pressed and held in its operative position by a spring 17 encircling the pivot pin 16 and having its opposite ends bearing against the rear face of the follower and front face of the mem- 100 ber 5.

What I claim is:

1. A follower mechanism comprising a guide in the form of a channel having its side margins overhanging its bottom, a follower, and clamping means associated with the follower including a slide extending in the front and the rear of the follower and

movable in the channel, and engaging the under sides of the overhanging margins, a member carried by the follower and coacting with the upper sides of said inturned margins directly above the rear end of the slide, substantially as and for the purpose described.

2. A follower mechanism comprising a guide in the form of a channel having its side margins overhanging its bottom, a follower and clamping means associated with the follower including a slide movable in the channel and engaging the under sides of the overhanging margins, the slide projecting in advance of the follower farther than it projects to the rear thereof, and a movable clamping member pivoted to the follower and located on the rear side thereof and coacting with the upper face of the overhanging margins of the guide at the rear end of the slide, substantially as and for the purpose specified.

3. A follower mechanism comprising a guide in the form of a channel having its side margins overhanging its bottom, a follower and clamping means associated with the follower including a slide movable in the channel and engaging the under sides of the overhanging margins, the follower being formed with a rearwardly extending lug, and the slide having an arm extending upwardly therefrom and passing contiguous to the lug, and a movable clamping member pivoted to said lug and the arm and coacting with the upper faces of said overhanging margins, the pivot for the clamping member serving to secure the follower, slide and clamping member together, substantially as and for the purpose set forth.

4. A follower mechanism comprising a guide in the form of a channel having its side margins overhanging its bottom, a follower and clamping means associated with the follower including a slide movable in the channel and engaging the under sides of the overhanging margins, the slide having a lengthwise intermediate portion raised above the bottom of the channel and extending lengthwise between the opposing edges of the said overhanging margins of the guide, the follower being provided with rearwardly extending lugs and the slide provided with upwardly extending arms located in rear of the follower and connected to the raised intermediate portion of the slide, and a movable clamping member pivoted to the lugs and said arms, the pivot of the clamping member serving to secure the follower, slide and clamping member together, substantially as and for the purpose described.

5. A follower mechanism comprising a guide in the form of a channel having its side margins overhanging its bottom, a follower and clamping means associated with

the follower including a slide movable in the channel and engaging the under sides of the overhanging margins, the follower having lugs at its lower edge coöoperating with the portion of the slide between the overhanging margins of the guide, substantially as and for the purpose specified.

6. A follower mechanism comprising a guide in the form of a channel having its side margins overhanging its bottom, a follower and clamping means associated with the follower including a slide movable in the channel and engaging the under sides of the overhanging margins, a portion of the slide being unprovided with side margins running under the overhanging margins of the guide, and the follower having lugs at its lower edge embracing said portion unprovided with side margins, substantially as and for the purpose set forth.

7. A follower mechanism comprising a guide in the form of a channel having its side margins overhanging its bottom, a follower and clamping means associated with the follower including a slide movable in the channel and engaging the under sides of the overhanging margins, a portion of the slide being unprovided with side margins running under the overhanging margins of the guide, and the follower having lugs at its lower edge embracing said portion unprovided with side margins, the slide being also provided with upwardly extending arms rising from said portion unprovided with margins said arms being located in the rear of the follower, and a clamping member pivoted to said arms and coacting with the upper faces of said overhanging margins, substantially as and for the purpose described.

8. A follower mechanism comprising a guide in the form of a channel having its side margins overhanging its bottom, a follower and clamping means associated with the follower including a slide movable in the channel and engaging the under sides of the overhanging margins, the slide having a lengthwise intermediate portion raised above the edge portions thereof which run under the overhanging margins of the guide, the follower being secured at its lower edge to said intermediate portion, and the follower being also provided with rearwardly extending lugs and the slide having arms extending upwardly from the said intermediate portion and passing contiguous to said lugs, and a movable spring-pressed clamping member pivoted to the arms and the lugs coacting with the upper faces of the overhanging edges of the guide at the rear end of the slide, substantially as and for the purpose specified.

9. A combination with a draw having lugs projecting from its bottom a follower and a follower mechanism comprising a guide in

the form of a channel having its side margins overhanging its bottom, the guide being formed with perforations in its bottom for receiving the lugs, and the lugs being bent 5 over onto the bottom of the channel; clamping means associated with the follower and including a slide movable into the channel and extending under the overhanging margins, the slide having a lengthwise intermediate portion raised above the bottom of 10 the channel and between opposing edges of the overhanging margins into position to

clear the lugs, substantially as and for the purpose set forth.

In testimony whereof, I have hereunto signed my name in the presence of two attesting witnesses, at Syracuse, in the county of Onondaga, in the State of New York, this 9th day of May, 1913.

EVERETT STUCK.
